UNITED STATES PATENT OFFICE.

ADOLPH F. JOHNSON, OF HANCOCK, MICHIGAN.

EASEL.

1,341,560.

Specification of Letters Patent. Patented May 25, 1920.

Application filed November 17, 1919. Serial No. 338,744.

To all whom it may concern:

Be it known that I, ADOLPH F. JOHNSON, a citizen of the United States, residing at Hancock, in the county of Houghton and State of Michigan, have invented new and useful Improvements in Easels, of which the following is a specification.

This invention relates to improvements in easels and has for an object the provision of an easel, which may be secured to a picture frame or picture mount to support the same upon a table or stand.

Another object of the invention is the provision of an easel of cheap and simple construction, which may be easily secured to either a picture frame or picture mount for the purpose above specified.

Other objects and advantages of the invention will appear as the following description is read in connection with the accompanying drawings.

In the drawings:

Figure 1 is a perspective view looking at the rear of a picture frame, with the invention applied thereto.

Fig. 2 is an elevation showing the parts of the invention separated.

Fig. 3 is a perspective view showing the invention applied to a picture mount.

Referring to the drawings in detail, like characters of reference denote corresponding parts throughout the several views.

In illustrating the invention, there is shown at 10 the frame of a picture. Se- 35 cured to the frame is an attaching member 11, the latter having located along one edge thereof a sleeve 12. The member 11 is made by folding over or bending upon itself a strip of metal. The sleeve 12 extends only 40 a portion of the length of the attaching member, about one-half of the said length. The attaching member is provided with apertures 13, by means of which the said member is secured to the frame. The easel 45 also includes an arm 14, which is substantially L-shaped, one edge of the arm being provided with a sleeve 15, while the other

edge is formed with a flange 16, the last named edge being preferably disposed at an acute angle with respect to the sleeve 15. 50

The attaching member 11 and the arm 14 are connected through the medium of an L-shaped pivot rod 17, the long arm 18 of which is slit within the sleeve 15 and the short arm 19 within the sleeve 12. This 55 provides for a free pivotal movement of the attaching member 11 upon the arm 19 and a similar movement of the arm 14 upon the arm 18, which permits of the proper adjustment of the said arm with respect to the 60 picture frame.

In Fig. 3 there is illustrated a form of the invention which is used for supporting an unframed picture or photograph. This includes a metal strip 20, which is adapted to 65 be inserted between the folds of the attaching member 11 and secured to the mount of a photograph for the purpose of holding the easel thereto.

The invention is susceptible of various 70 changes in its form, proportions and minor details of construction and the right is herein reserved to make such changes as properly fall within the scope of the appended claims.

Having described the invention, what is claimed is:

1. An easel comprising a supporting leg, a sleeve located along one edge thereof, an attaching member, a sleeve also located 80 along one edge of the attaching member and an L-shaped rod having one arm positioned within the sleeve of the leg and the other arm positioned within the sleeve of the attaching member to provide for a pivotal 85 movement of both the leg and attaching member upon the rod.

2. The combination with a frame, of a supporting leg therefor, and means for securing the leg to the frame in a manner to 90 permit of vertical and horizontal pivotal movement.

In testimony whereof I affix my signature.
ADOLPH F. JOHNSON.
